[57] CLAIM

The ornamental design for a compact disk indexing tab, as shown and described.

DESCRIPTION

FIG. 1 is a perspective view of an indexing tab for a compact disk case showing my new design, the undisclosed rear portion is a mirror image of the front shown;

FIG. 2 is a front elevation view of FIG. 1;

FIG. 3 is a top plan view of FIG. 1;

FIG. 4 is a bottom plan view of FIG. 1;

FIG. 5 is a right side elevation view of FIG. 1;

FIG. 6 is a left side elevation view of FIG. 1;

FIG. 7 is a perspective view of a modified embodiment of the indexing tab illustrated in FIG. 1, the undisclosed rear portion is a mirror image of the front shown;

FIG. 8 is a front elevation view of FIG. 7;

FIG. 9 is top plan view of FIG. 7;

FIG. 10 is a bottom plan view of FIG. 7;

FIG. 11 is a right side elevation view of FIG. 7; and,

FIG. 12 is a left side elevation view of FIG. 7.
